UNITED STATES PATENT OFFICE.

FREDERIC G. NICOLAUS, OF CLEVELAND, OHIO, ASSIGNEE TO AMERICAN STOVE
COMPANY, OF ST. LOUIS, MISSOURI, A CORPORATION OF NEW JERSEY.

STOVE-FRAME.

1,178,259.

Specification of Letters Patent.

Patented Apr. 4, 1916.

Application filed January 9, 1915. Serial No. 1,397.

To all whom it may concern:

Be it known that I, FREDERIC G. NICOLAUS, a citizen of the United States, residing at Cleveland, in the county of Cuyahoga and State of Ohio, have invented certain new and useful Improvements in Stove-Frames, of which the following is a specification, reference being had therein to the accompanying drawing.

10 My invention relates to improvements in stove frames.

The object of my invention is to provide a stove frame made of angle iron which is very rigid and unbreakable and at the same time producing a frame in which all of the horizontal and vertical joints are flush, thus producing a more simple, cheap and practical stove frame.

Another object of my invention is to produce a stove frame which is readily assembled and which has certain details of structure and combination of parts herein-after more fully set forth.

In the accompanying drawings—Figure 25 1 is a perspective view of my improved stove frame. Fig. 2 is a plan view of the angle iron forming the upper top burner frame, before being bent and showing the cutaway portion to allow for forming the corners. 30 Fig. 3 is a plan view showing the angle iron bent to form the corner or angle of the frame. Fig. 4 is a plan view of the angle iron forming the lower frame having the cutaway portion in the shorter leg of the 35 angle iron and showing the semi-circular notches. Fig. 5 is a plan view showing the angle iron bent to form the angle or corner of the frame and providing an opening for the insertion of the bolt for

allowing the insertion of the bolt for the leg. Fig. 6 is a side elevation showing the dovetail connection between the vertical door-frame and the horizontal bottom frame. Fig. 7 is a vertical sectional view taken on the line 7-7, Fig. 6. Fig. 8 is a sectional view showing the means for securing the two abutting ends of the angle iron together to form the frame. Fig. 9 is a plan view of an angle iron showing a modified cut-away portion to allow for forming the corners. Fig. 10 is a plan view showing the angle iron bent and showing the cut-away portions fitting tightly together.

Referring now to the drawings, 1 repre-

sents a base of my improved stove frame and is formed of a continuous piece of angle iron bent in a rectangular form and secured together at 2, by means of a short piece of angle iron 3, fully shown in Fig. 1, of the drawings. 55

In forming the base of the stove-frame, a piece of angle iron of proper length is taken and at the proper intervals thereon the short leg 4 of the angle iron has stamped therefrom the triangular portions 5. The cut-away portions have semi-circular cut-away portions 6 oppositely arranged, as shown in Fig. 4, and when the long or vertical leg of the angle iron is bent at the apex of the cut-away portions to bring the edges of the said cut-away portions together and to form a right angle, the two semi-circular portions form a circular opening 7, through which passes a bolt by means of which the stove leg is secured to the base. The long leg of the angle iron, as shown, is vertically disposed so as to give greater strength to the frame and by thus forming the base it will be seen that the corners have a neat appearance and at the same time providing a more rigid frame than could be formed by securing a number of pieces of angle iron together to form such a frame. The legs 8 rest against the lower face of the short leg 4 of the base 1, and are provided with an opening through which a bolt passes and the bolt also passes through the opening 7 formed at the corner of the base. In order to prevent the legs from twisting they are provided with ears 9, which extend upwardly and engage the outside of the vertical portion of the angle iron.

The ends of the angle iron, as heretofore stated, abut and are held in said abutting position by means of the short piece of angle iron 3, and passing through the corner of the base 1 are bolts 10, which pass through the angle iron 3 and have secured thereon nuts 10, as fully shown in Fig. 8 of the drawings. The vertical portion 11 of the angle iron forming the base is provided with dovetailed notches 12, communicating with the upper edge of the angle iron and into which fits the dovetailed portion 13 of the standards 14, 15 and 16. 105 100

The standards 15 and 16 form the door-

frame for the upper and lower ovens and are constructed of a single piece of angle iron provided with the cut-away portions at the corners to form the rectangular frame shown in Fig. 1. In order to hold the dovetailed portions 13 in the recesses 12, a bolt 17 passes through an opening 18, half of which is in the vertical portion 11 of the angle iron forming the base and the other half of the opening in the lower end of the dovetailed portion 13. This bolt passes loosely through a washer 19, which is of a length to overlap the ends of the recess 12, as fully shown in dotted lines, Fig. 6. Secured on the bolt 17, on the outside of the washer 19, is a nut 20, and by tightening the bolt 17, it will be seen that the standards 14, 15 and 16 will be flush with the vertical portion 11 of the angle iron forming the base.

In order to provide the frame forming the front or door-frame of the oven, a transverse angle iron 21 is provided, which has a dovetailed connection with the standards 15 and 16, arranged in precisely the same manner as that heretofore described and, therefore, this connection will not be more fully described.

Secured to the upper end of the standard 14, is a top frame 22 of the stove, which like the base 1, is formed of angle iron which is arranged in a reverse position to that of the base. That is, the longer leg of the angle iron is arranged in a horizontal position and, therefore, the said longer leg is provided at proper intervals with cut-away portions 22', which allow the angle iron to be bent into a rectangular frame to form the top of the stove. The two abutting ends 23 and 24 of the angle iron forming the top are secured together by a short piece of angle iron, the same as that described in respect to the base 1.

While I have shown and described this specific arrangement of the base, top and over-door frame, it will be understood that these are varied in different forms of stoves and, therefore, I do not lay any stress upon this specific arrangement of the same.

The invention is in forming a stove-frame of angle iron so that the different frames are formed of continuous pieces of angle iron bent to form the different rectangular frames and said frames secured together with their outer faces flush.

Having thus described my invention, what I claim and desire to secure by Letters Patent is:

1. A rectangular frame comprising a strip of angle iron of a length equal to the perimeter of the frame, one leg of the angle iron having four cut-out portions equal to a right angle, the other leg of the angle iron bent at points located at the apex of the cut out portions, the ends of the strip pulled together to

cause the edges of the cut-out portions to firmly abut and the ends fastened together to hold the edges abutting, thus holding the frame in its completed shape with the edges of all of the cut-out portions firmly abutting.

2. A rectangular frame comprising a strip of angle iron of a length equal to the perimeter of the frame, one leg of the angle iron having four cut-out portions equal to a right angle and located at equal distances apart forming two ends projecting beyond the cut-out portions of a combined length equal to the space between the cut out portions, the other leg of the angle iron bent at points located at the apex of the cut-out portions, the ends of the strip pulled tightly together and fastened thereby causing the edges of the cut-out portions to tightly abut and to hold them in their abutting positions, thus firmly holding the frame in its completed shape with the surface of the cut-out portions flush throughout its perimeter.

3. An angular frame comprising a strip of angle iron of a length equal to the perimeter of the frame, one leg of the angle iron having cut-out portions equal to the desired angle of the frame, the other leg of the angle iron bent at points located at the apex of the cut-out portions, the ends of the strip pulled tightly together to cause the edges of the cut-out portions to firmly abut, and the said ends firmly fastened to hold the said abutting edges firmly together and to hold the frame in its completed shape.

4. A stove frame comprising a base frame formed of a strip of angle iron having V-shaped cut-away portions in one leg and the other leg bent to form the corners of the base with flush vertical and horizontal walls, a door frame formed of angle irons in like manner and having a dovetailed connection with the vertical leg of the base frame, a bolt intersecting the dove-tailed opening in the base and a washer on the rear of the said bolt and engaging the dovetailed portion of the door-frame and the face of the vertical leg of the base.

5. A stove base formed of a strip of angle iron of a length equal to the perimeter of the base, the horizontal leg of the angle iron having V-shaped cut-away portions provided with recesses and said recesses adapted to form an opening when the vertical leg of the angle iron is bent to form a rectangular base to provide means for securing the stove leg thereto.

6. A stove frame comprising a base frame formed of a strip of angle iron having cut-away portions in one leg and the other leg bent to form the corners of the base with flush vertical and horizontal walls, a door frame formed of angle irons in like manner and having a flush connection with the vertical leg of the base frame, a bolt intersecting the connection in the base and a washer

on the rear of the said bolt and engaging the connection of the door-frame and the base of the vertical leg of the base.

7. A rectangular metal frame comprising a strip of angle iron of a length equal to the perimeter of the frame, four rectangular portions cut out of one leg of the angle iron, the other leg of the angle iron bent at a point opposite the center of the cut-away portion, and said cut-away portion arranged at the four corners of the rectangular frame, a door frame formed of angle iron from a continuous sheet of metal having a cut-away portion to form flush vertical and horizontal walls, the door frame having a flush connection with the base frame.

8. An angular frame comprising an angle

iron of a length equal to the complete perimeter of the frame, one leg of the angle iron having cut-out portions equal to the desired angular shape of the completed frame, the ends of the strip projecting beyond the cut-away portions, and means connecting the ends of the strip, thus making a complete frame capable of being bodily incorporated in a structure and to hold its shape irrespective of the other parts of the structure in which it is incorporated.

In testimony whereof I hereunto affix my signature in the presence of two witnesses.

FREDERIC G. NICOLAUS.
